UNITED STATES PATENT OFFICE.

JOHN A. KNISELY, OF CHICAGO, ILLINOIS.

WINDOW-LOCK.

SPECIFICATION forming part of Letters Patent No. 683,650, dated October 1, 1901.

Application filed June 21, 1901. Serial No. 65,533. (No model.)

To all whom it may concern:

Be it known that I, JOHN A. KNISELY, a citizen of the United States, residing at Chicago, in the county of Cook and State of Illinois, have invented certain new and useful Improvements in Window-Locks; and I do hereby declare the following to be a full, clear, and exact description of the invention, such as will enable others skilled in the art to which it appertains to make and use the same.

My invention relates to improvements in window-locks of the class adapted for locking or latching pivoted metal sash to sheet-metal window-frames.

15 The object of my improvements is to provide a lock that will hold the sash securely to the frame, so that it will not rattle, that will serve the double purpose of a spring latch or lock and a lever opener or starter, and that 20 will be certain or positive in its action under the varying conditions met in sheet-metal construction. Having these purposes and others of simplicity in use and economy of construction in view, I have designed the lock 25 hereinafter described, and illustrated in the accompanying drawings, in which—

Figure 1 is a view, partly in elevation and partly in vertical section, representing my improved lock applied to a metal window-sash 30 pivoted and locked on a metal frame, only the top portion or lintel of the latter being shown. Fig. 2 is a view of the same character as Fig. 1; but the sash is shown as unlatched and slightly tilted. Fig. 3 is a detail in side elevation of the lock alone. Fig. 4 is a front elevation of the lock, and Fig. 5 comprises end and bottom views of the plate on which the lock is pivoted.

Referring to the drawings in detail, a represents the lintel or top box of a sheet-metal window frame or casing.

b is the top rail of a sheet-metal window-sash, and b' one of the stiles of same.

c is the latch or lock, and d the plate on 45 which the lock is pivoted and which is riveted to projecting portions or flanges of the top rail.

In the construction of sheet-metal window-frames in order to provide the requisite stiffness and secure a close joint between the top 50 of the frame and sash the former is preferably made with a series of bends, as shown, thus providing the flat vertical faces a', a²,

and a³, the last two serving as meeting edges and stops for the sash. In the horizontal face a⁴ of the frame a square opening a⁵ is cut to 55 receive the end c' of the lock-bolt c⁶ when the sash is closed. The top rail of the sash is formed with an angular extension or flange b², the vertical portion of which abuts against the face a² of the window-frame, and the horizontal portion lies under the portion a⁴ of the frame and is perforated, as at b³, to admit the end of the lock-bolt.

The angular plate d is riveted to both vertical and horizontal portions of the sash-flange, with its square hole d' registering with the opening b³. This plate serves to reinforce the sash-flange and also affords a support for the lock, which is pivoted on a pin d⁸ between the lugs d² of the plate. The pivotal point c³ of the lock being above its center and the lower part of the lock being much heavier than the upper part, it will swing outwardly from the sash as soon as the bolt is withdrawn from the frame and the sash tilted 75 or swung inwardly.

The lock-casing c is formed with a barrel portion c' and an upwardly-extending flat arm c², in which the pivot-opening is provided. The portion c' is bored to receive a 80 coil-spring c⁵ and a latch-bolt c⁶. The latch-bolt is formed with a square portion c⁷, which rests on the spring, and a round stem c⁸, which passes through the spring and projects below the barrel of the casing, where it receives a ring e, to which a pull cord or chain e' is attached, said ring preventing the latch-bolt from being pushed out of the barrel by the spring. The upper end of the bolt is 85 beveled and is formed with shoulders c⁹ on 90 opposite sides which strike against the upper edge of the barrel when the bolt is retracted, thus limiting the retractive movement of the bolt and taking the strain from the spring as the pull is continued to swing 95 or open the sash. The spring serves to shoot the bolt into the opening a⁵ in the lintel. When the bolt is retracted to the full limit permitted by its shoulders c⁹, it will be entirely free from the frame and the sash may 100 swing on its pivots. In metal windows the sash are usually held by frictional contact with spring-pressed jambs or stiles, which require more or less force to cause them to turn

on their pivots. By pulling on the cord e' the lower end of the lock is drawn away from the sash, while the upper portion or arm c^2 is pressed against the lintel of the frame, thus 5 acting as a lever in forcing the sash away from the frame. This leverage may be increased by lengthening the stem of the bolt. The pull on the cord e' being first communicated to the spring, the tension of the latter 10 will effect a gradual yielding of the bolt, which will be communicated to the lock-casing, so that when the sash is ready to swing it will move slowly and gradually and not with a jerk, as it would if the pull was directly and quickly applied. As the sash are 15 usually hung above their center, they will close on the frame by gravity, and the beveled end of the latch-bolt striking against the corner of the frame will be retracted until it 20 gets opposite the opening a^5 , when the spring will shoot the bolt into said opening and the sash will be securely locked.

Having thus described my invention, what I claim as new, and desire to obtain by Letters 25 Patent, is—

1. A window-lock composed of a casing having a barrel portion, a latch-bolt and a spring arranged in said barrel portion, an arm extending upwardly and outwardly from the 30 barrel portion and a plate on which said arm is pivoted, substantially as set forth.

2. A window-lock composed of a casing having a barrel portion, a spring arranged in said portion, a latch-bolt arranged in said portion 35 and resting on said spring, and formed with shoulders adapted to limit its retraction, an arm extending upwardly and outwardly from the barrel portion of the casing, and a plate on which said arm is pivoted, substantially as described. 40

3. A window-lock composed of a casing having a barrel portion, a spring arranged in said portion, a latch-bolt arranged in said barrel

and resting on said spring, said bolt being formed with a beveled end, with shoulders 45 back of said end and with a stem extending through said casing, a ring or the like in said stem, an arm extending upwardly and outwardly from the barrel portion of the casing, and a plate on which said arm is pivoted, as 50 set forth.

4. The combination with a window-frame having angular faces substantially as described, a sash horizontally pivoted on said frame, a lock secured to said sash, said lock 55 composed of a casing having a barrel portion, a spring arranged in said barrel, a latch-bolt in said barrel and resting on said spring, means for limiting the retraction of said bolt, means for retracting said bolt, an arm extending upwardly and outwardly from the barrel portion of the casing, and a plate on which said arm is pivoted, said plate securing the lock to the sash, substantially in the manner and for the purpose set forth. 65

5. The combination with a window-frame having angular faces substantially as described, a sash horizontally pivoted on said frame and provided with a flange, a plate secured to said flange and having a bolt-opening therein, a lock pivoted on said plate, said lock provided with a barrel portion, a coil-spring located in said barrel, a latch-bolt arranged in said barrel and resting on said spring, said bolt having shoulders adapted to 70 limit its retraction, an arm extending from said casing adapted to contact with said frame when the sash is closed against the frame, and means for retracting said bolt, substantially as set forth. 75

In testimony whereof I affix my signature in presence of two witnesses.

JOHN A. KNISELY.
